(73) Assignee: **Intec, Inc.**, Miami, FL (US)

(57) **CLAIM**

(**) Term: **14 Years**

The ornamental design for multi-link device for a video game device, as shown and described.

(21) Appl. No.: **29/164,617**

DESCRIPTION

(22) Filed: **Jul. 29, 2002**

FIG. 1 is a front view of the multi-link device for a video game according to the present invention.

(51) **LOC (7) Cl. 21-01**

FIG. 2 is a rear view of the multi-link device for a video game device of FIG. 1.

(52) **U.S. Cl. D21/333**

FIG. 3 is a top view of the multi-link device for a video game device of FIG. 1.

(58) **Field of Search D21/324-333,**

FIG. 4 is a bottom view of the multi-link device for a video game device of FIG. 1.
